assignor to

Lowell Manufacturing Company, same place.
Letters Patent No 1210. Dated Feb. 28. 1860.

The schedule referred to in these Letters Patent and making part of the same,

To all whom it may concern:

Be it known that I, Clemir J. Ney, of Lowell, in the County of Middlesex, and State of Massachusetts, have originated and designed a new pattern for Carpets or other fabrics, of which the following is a full, clear and exact description, reference being had to the accompanying drawings making part of this specification.

The center A. consists of a large group of fruit, flowers and leaves, resting on the broad Bars B. and C. which run at right angles with each other and terminate in the corners.

The space between said bars is occupied by the wavy grounds

1. 2. 3 & 4.

The colors employed for the different portions of the design may be varied to suit the taste and wish of the manufacturer.

Claim.

What I claim as my invention, and desire to secure by letters patent, is the design or pattern for Carpets herein set forth.
